CIRCUIT BREAKER

Albert H. Baylis, North Irwin, Pa., assignor to Westinghouse Electric & Manufacturing Company, East Pittsburgh, Pa., a corporation of Pennsylvania

Application December 17, 1941, Serial No. 423,368

15 Claims. (Cl. 171—97)

The invention relates to circuit breaker systems and more particularly to an interlocking arrangement for interlocking a plurality of circuit breakers.

One object of the invention is the provision of an electrical system having a plurality of circuit breakers and a novel electrical interlock arrangement for the breakers to prevent closing of an open breaker while another breaker is in closed position and in which mechanical means is provided to prevent the closed breaker from tripping out due to a loss of control energy in the interlocking circuit.

Another object of the invention is the provision of a plurality of circuit breakers with an improved electrical interlock which prevents closing of one circuit breaker while the other is closed and in which mechanical means prevents the functioning of the interlock associated with the closed breaker due to loss of control energy for the interlock circuit.

Another object of the invention is the provision of an improved interlocking control system for two circuit breakers wherein each breaker is provided with electroresponsive means controlled from the other breaker for preventing closing of one breaker while the other breaker is closed and in which each breaker is provided with means for preventing operation of its own electroresponsive means when in closed position.

Another object of the invention is the provision of an improved control device for a circuit breaker embodying an electroresponsive trip means adapted to be controlled from a second breaker to effect tripping of the circuit breaker if said breaker is operated to closed position when the second breaker is closed.

Another object of the invention is to provide an improved control device for a circuit breaker comprising an electroresponsive trip means which is controlled by a second breaker when the second breaker is closed to prevent closing of the first breaker, and which is provided with a mechanical member to positively prevent operation of the trip means when the first breaker is in closed position.

Another object of the invention is the provision of a circuit breaker embodying an auxiliary trip device biased to cause tripping of the breaker wherein the trip device is prevented from operating by an electromagnetic means controlled by a second breaker and in which a mechanical member is operated by the breaker when the breaker is closed to prevent operation of the auxiliary trip device.

The novel features that are considered characteristic of the invention are set forth in particular in the appended claims. The invention itself, however, both as to structure and operation, together with additional objects and ad-

vantages thereof, will be best understood from the following description of a single embodiment thereof when read in conjunction with the accompanying drawings in which:

5 Fig. 1 is a side elevational view of one three pole circuit breaker embodying the interlocking arrangement of the invention.

Fig. 2 is a vertical sectional view through the center pole of the breaker.

10 Fig. 3 is a diagrammatic view showing two circuit breakers interlocked by the interlocking arrangement of the present invention and showing the interlock control circuit, and

Fig. 4 is an enlarged sectional view taken on 15 the center line of the resilient linkage of the interlocking mechanism.

The two electrically interlocked circuit breakers are of identical construction and hence the details of construction of one will be sufficient.

Referring to Fig. 2 of the drawings which shows one of the electrically interlocked breakers, the circuit breaker is provided with an operating mechanism common to all of the poles which is mounted in a U-shaped main frame 16 comprising a pair of frame members 17 rigidly connected by a cross member 19. The frame 16 is mounted on the central portion of a base 11 of insulating material and is secured thereto by means of bolts 21 and 23. The outer ends of the frame members 17 are rigidly connected by a cross member 25.

The bolt 23 extends through the base 11 and cross member 19 and serves to rigidly secure a connector 21 of conducting material to the cross member and to the base 11. A shaft 29 extending through an opening in the connector 21 and through openings in the frame members 17 pivotally supports a pair of arms 31 having their free ends integral with a contact arm 30 for the center pole. The contact arms 30 (Fig. 1) for the outer poles are identical with the arm 30 for the center pole but are not provided with arms 31. The contact arms 30 for the outer poles are rigidly secured to a tie bar 67 which extends across all of the poles and which is clamped to the center pole contact arm 30 by means of a split clamp 70 and a screw 71. Rectangular tubes 69 of insulating material between the tie bar 67 and contact arm 30 for the several poles serve to insulate 50 the three movable contact arms and their associated contacts from the tie bar 67.

The movable contact structures and the stationary contacts for the several poles are alike for which reason only the contacts for the center poles will be described. The contact arm 30 for the center pole pivotally carries a main movable contact member 41 and a movable arcing contact member 55. The main contact member 41 is pivoted on a pivot pin 49 supported in projections 51 of the contact arm 30, and the mov-

able arcing contact member 55 is pivoted on a pivot pin 57 supported in projections 59 of the arm 30. The main movable contact member 47 carries a contact 33, and a contact 35 is secured to the arcing contact member 55. These contacts 33 and 35 are adapted to engage respectively fixed contacts 39 and 37 secured on a conductor 41 which is in turn secured to the base 11 by means of bolts 43. The conductor 41 extends upwardly and is bent at right angles, the bent portion extending through an opening in the base 11 to form a terminal connector 45.

A spring 63 compressed between a spring seat on the contact arm 30 and a spring seat on the main contact member 47 provides contact pressure for the main contacts 33-39 when the contact arm is in the closed position. Contact pressure for the arcing contacts 35-37 is provided by a spring 63 surrounding a rod 61 pivotally connected to the arcing contact member 55 and slideable through an opening in a spring seat on the contact arm 30. The spring 63 is compressed between a washer 65, seated on a shoulder on the rod 61, and the spring seat on the contact arm 30. The rod 61 has a nut 75 on the outer end thereof which acts to limit counterclockwise rotation of the arcing contact member 55 about its pivot when the contact arm 30 is moved to open the contacts. Counterclockwise movement of the main contact member 47 is limited by a projection 73 thereon striking the body of the contact arm 30. The adjustment of the nut 75 on the rod 61 is such that the arcing contacts 35-37 open after the main contacts 33-39 open during an opening operation of the circuit breaker and close before the main contact closes during a closing operation.

When the contact arm 30 is operated to open the contacts, the arc across the arcing contacts 35-37 resulting from the rupture of the current is drawn into an arc extinguisher indicated generally at 16 where it is cooled and extinguished. Any suitable arc extinguisher may be employed, the one illustrated comprising, generally, a stack of slotted magnetic plates disposed adjacent the paths of travel of each of the arcing contacts 35. The plates serve to draw the arc towards the ends of the slots where it is broken up into a plurality of short arcs which are quickly cooled and extinguished.

The movable arcing contact member 55 is connected by a flexible shunt conductor 77 to the main contact member 47 and another flexible shunt conductor 79 connects the main contact member 47 to the connector 27. The connector 27 for the center pole is secured to the cross member 19 of the frame 16 by the bolts 23, and the connectors 27 for the outer poles are bolted to the base 11 with a spacer 28 (Fig. 1) between the base and each of these connectors in order to align the members 27 of the outer poles with the corresponding members 27 for the center pole. A conductor 81 (Fig. 2), secured to the connector 27 by means of bolts 14 extends downwardly therefrom and is bent at right angles. The horizontally disposed portion of the conductor extends between the legs of a U-shaped tripping magnet core 161 and projects through an opening in the base 11 where it forms a terminal connector 83 which, together with the terminal connector 45, serves to connect the pole of the breaker in an electrical circuit.

The electrical circuits for the several poles of the breaker are essentially the same, therefore, only the circuit for the center pole will be traced.

This circuit extends from the terminal connector 45 through the conductor 41, the main contacts 33-39, the main contact member 47, the flexible shunt conductor 79, the connector 27, the conductor 81 to the terminal connector 83. The circuit for the arcing contacts 37-35 extends from the terminal connector 45, through the conductor 41, the arcing contacts 37-35, the flexible shunt conductor 77, the main contact member 47 and through the previously described circuit to the terminal connector 83.

The contact arms 30 are biased in a clockwise or opening direction by means of a pair of springs 85 (Figs. 1 and 2). These springs are tensioned between the center pole contact arm 30 and a fixed pivot 81 supported in the main frame 16. In the closed position of the breaker, the center pole contact arm 30 and consequently all of the contact arms are releasably restrained in closed contact position (Fig. 2) by means of a toggle and linkage mechanism which is collapsible to cause opening of the contacts. The toggle and linkage forms a part of the common operating mechanism.

This collapsible linkage includes a lever 89 pivotally mounted on a fixed pivot 81 supported on the main frame 16. The lever 89 comprises a pair of levers rigidly connected by an integral cross bar 117, and is operatively connected to the support arms 31 of the center pole contact arm 30 by a main operating toggle comprising toggle links 93 and 95. The toggle link 93 has one end pivoted on a pin 101 supported on the lever 89 and the link 95 is pivoted on a pivot pin 99 on the arm 31. The links 93 and 95 are pivotally connected by a knee pivot pin 97. The toggle link 95 comprises a pair of links rigidly connected by means of an integral cross bar 115.

The free end of the lever 89 is connected by means of a link 103 to one arm of a lever 105 pivoted on a fixed pivot 81. The other arm of the lever 105 is pivotally connected to a toggle link 107 of a tripping toggle comprising the link 107 and a toggle link 109. The link 109 is pivoted on a fixed pivot 113 supported on the frame 16 and comprises a pair of links joined near the pivot 113 by a yoke 123 provided with projections 125 and 127. The toggle link 107 comprises a pair of links connected by a yoke 119 having a bent portion to which is secured an extension 121 of insulating material. The toggle links 107 and 109 are pivotally connected by a knee pivot pin 111. The purpose of the extension 121 is to cooperate with a part (not shown) connected to a manually operable handle 141 to manually trip the breaker in a manner to be more fully described later. The lever 105 and the link 103 each comprise a pair of members rigidly connected by yokes substantially as illustrated.

The linkage just described serves to releasably hold the contact assemblage including the movable contacts for all of the poles of the breaker in closed contact position. In the closed position, the main operating toggle 93-95 is overcenter above a line through the center of the pins 99-101, and a second toggle, one link of which comprises the overcenter links 93-95 and the other link of which comprises the lever 89, is overcenter above a line through the center of the pins 99 and 91. The overcenter movement of the main operating toggle 93-95 is limited by the projecting end of the link 93 engaging the cross bar 115 of the link 95.

With the main operating toggle 93-95 and the toggle comprising the links 93-95 and the lever

89 in the overcenter position, as shown in Fig. 2, the springs 85 bias the lever 89 in a clockwise direction. Movement of the lever 89, however, is normally prevented by the tripping toggle 107-109 which is overcenter to the left of a line through the center of the fixed pivot 113 and the point of connection of the toggle link 107 with the lever 105. The toggle 107-109 is biased to its overcenter position by a spring 128 tensioned between the yoke 119 and the fixed pivot 113. The overcenter position of the tripping toggle 107-109 is adjustably determined by the projection 125 of the yoke 123 engaging an adjusting screw 129 in the cross member 25 of the frame. The tripping toggle 107-109 in its overcenter position, acting through the lever 105 and the link 103, prevents clockwise movement of the lever 89 and consequently holds the movable contact assemblage in the closed contact position against the biasing influence of the springs 85.

The tripping toggle 107-109 is adapted to be moved overcenter outwardly in a direction to cause its collapse to effect opening of the contacts by means of a current overload trip device indicated generally at 133 (Figs. 1 and 2). The trip device is operable in response to overload currents in the circuits of the breaker to actuate a trip rod 135 and cause collapse of the tripping toggle 107-109. The trip rod 135 is slidably vertically through a shunt trip coil (not shown) enclosed in a casing 138 attached to the main frame 16. The shunt coil is adapted to be energized from a suitable source and in a manner well known in the art, to operate the trip rod and trip the breaker from a remote point.

When operated either by the shunt coil or by the current overload trip device 133, the trip rod 135 is thrust upwardly and strikes the projection 127 of the yoke 123 and rocks the toggle link 109 clockwise about the fixed pivot 113. This movement of the link 109 causes collapse of the tripping toggle 107-109 permitting clockwise movement of the lever 89 which permits the springs 85 to rock the movable contact assemblage clockwise to open the contacts.

The main operating toggle 93-95 does not immediately collapse but the force of the springs 85 applied through the contact arms 30-31 and the main operating toggle causes collapse of the toggle comprising the links 93-95 and the lever 89 which results in clockwise movement of the lever 89. This movement is transmitted through the link 103 and the lever 105 to complete the collapse of the tripping toggle 107-109.

The clockwise or opening movement of the contact arm 30 is arrested by projections (not shown) thereon striking portions 137 of the frame members 17 of the main frame 16. At this time the rebound of the inertia of the main operating toggle 93-95 and the parts of the linkage 89, 103 and 105 starts the main operating toggle overcenter in a direction to cause its collapse. By the time the knee pin 97 of the toggle has passed overcenter below the line 99-101 the weight of the parts acts to complete the collapse of the toggle 93-95 and causes the linkage 89, 103, 105 and the tripping toggle 107-109 to be automatically reset to their normal position. The main operating toggle 93-95 remains in collapsed condition until the contacts are closed.

The contacts are closed manually by operation of the previously mentioned handle 141. The handle is rotatably mounted in a bracket 143 of insulating material secured to the outer end of the main frame 16. Operatively connected to

- the mechanism (not shown) operated by the handle is a link 151. The lower end of the link 151 is recessed and straddles a pulley-shaped member 153 mounted on a cross member 147 rigidly connecting the outer ends of a pair of spaced contact closing levers 145. These levers are disposed on the outside of the frame 16 and are pivotally supported on the ends of the fixed pivot 91 which project beyond the frame members 17. The inner ends of the lever 145 are rigidly connected by a cross member 149. Spaced projections 152 extending from the center portion of the cross member 149 support a pivot pin 157 upon which is rotatably mounted a roller 155. The contacts are closed manually by clockwise rotation of the handle 141. This movement of the handle, through connections (not shown) thrusts the link 151 downwardly and due to its engagement with the member 153, rotates the closing lever 145 in a clockwise direction. During this movement of the lever 145, the roller 155 engages the link 93 of the now collapsed main operating toggle 93-95 and moves this toggle to its overcenter position. Since at this time the tripping toggle 107-109 has been restored to its overcenter position, rotation of the lever 89 is prevented and consequently the force applied by the roller 155 to straighten the toggle 93-95 rotates the contact arm 30 counterclockwise to close the contacts and to tension the springs 85. The clockwise movement of the closing lever 145 moves the toggle 93-95 overcenter above the line 99-101 so that the contacts are held in the closed position until the breaker is again tripped. Upon release of the handle 141 following a contact closing operation, a spring 159 tensioned between the closing lever 145 and the frame 16 restores the lever 145 in a counterclockwise direction. This movement of the lever 145 and the member 153 thrusts the link 151 upwardly to restore the handle 141 to its neutral position. The closing lever 145 may be operated to automatically close the contacts through the agency of a motor 139 (Fig. 2) mounted on a plate attached to the side of the frame 16. The motor 139 may be energized from any suitable source. When energized, the motor is adapted, through a suitable driving connection, to rotate a crank disc 130. This disc carries an anti-friction roller 131 which engages a cam face 132 on an arm 134 secured to one side of the closing lever 145 and rotates the arm and the closing lever 145 clockwise to effect closing of the contacts in the previously described manner. As soon as the roller 131 passes out of engagement with the arm 134, the spring 159 acts to restore the lever 145 to its normal position. The motor 139 is deenergized by a suitable limit switch (not shown). The circuit breaker may be tripped manually by rotation of the handle 141 through a small angle in a counterclockwise direction from its neutral position. When the handle is rotated in tripping direction, a projection (not shown) on the link 151 engages the extension 121 on the yoke 119 of the toggle link 107 and rocks the link counterclockwise about its point of pivotal connection with the lever 105. This moves the tripping toggle 107-109 overcenter in a direction to cause its collapse and effects opening of the contacts in the previously described manner.

As previously stated, the trip rod 135 is operated to effect tripping of the breaker by means of a current responsive trip device 133. There is a trip device 133 provided for at least two of the

poles of the breaker but since the trip devices are alike only the one for the center pole will be described.

The trip device includes the U-shaped magnet core 161 and a frame comprising substantially parallel side members 163 rigidly connected at their outer ends by a yoke 165. The members 163 are provided with mounting feet 167, and bolts 169 extend through openings in the feet 167 and in the magnet core 161 and in the base 11 to rigidly secure the core and frame to the base. A trip lever 173 is pivotally supported on a pivot 175 mounted in the frame 163. The trip lever 173 comprises a pair of spaced levers having an armature 179 secured to one end and being rigidly connected by a yoke 177 at the other end. The trip lever 173 is biased against operation by the magnet 161, by means of a pair of springs 191 (Fig. 2) having one end secured to the yoke 177 and the other end attached to a vertically movable plate 193. The plate 193 cooperates with an adjusting screw 195 which is provided with a knurled head 197 bearing against the bottom side of a formed projection 199 of the yoke 165. Rotation of the screw 195 moves the plate 193 and thereby adjusts the tension of the spring 191 to vary the tripping point of the breaker. A scale plate 203, supported on spaced projections 201 of the yoke 165, bears indicia indicating the adjustment of the spring 191 or the tripping point of the breaker. An adjustable stop screw 205 provided with a lock nut 207 determines the open air gap of the magnet.

A trip bar 187 is rotatably supported in a bracket 189 secured to the casing 138 for the shunt coil. The trip bar extends across all of the poles of the breaker and is provided with an arm 185 for each pole, the center one of the arms being in alignment with the lower end of the trip rod 135. An adjusting screw 181 is mounted in each of the yokes 171 in alignment with the corresponding arm 185.

Normal rated current flowing through the circuit of the breaker, including the conductor 81, causes slight energization of the magnet 161 but not sufficient to overcome the tension of the springs 191. Upon the occurrence of an overload current above a predetermined value in the circuit of any pole, the flow of current through the corresponding conductor 81 causes energization of the magnet sufficient to overcome the springs 191 and attract the armature 179 rocking the trip lever 173 counterclockwise. At this movement of the trip lever 173, the screw 181 rotates the arm 185 and the trip bar 187 in a clockwise direction and thrusts the trip rod 135 upwardly to trip the breaker in the previously described manner.

Figure 3 illustrates diagrammatically an electrical control system wherein two circuit breakers of the type hereinbefore described indicated generally at A and B are utilized to selectively connect independent supply circuits 3 and 4 to a load circuit 5. In such systems it is desirable to prevent closure of one breaker while the other is closed to avoid connecting both source circuits to the load circuit at the same time. It is also desirable to prevent the closed breaker from tripping out in response to a loss of energy in the control circuit.

Each of the breakers A and B is provided with an interlocking device indicated generally at 208a and 208b (Fig. 3). These interlocking devices are identical and therefore only one will be described. Each of the interlocking devices includes an elec-

tromagnet 209 (Fig. 1) comprising an E-shaped core 211 rigidly mounted between the legs of a U-shaped frame 213 secured to the base 11 adjacent the left hand pole as viewed from the front of the breaker. Each of the two outer legs of the magnet core is surrounded by a coil 217, the two coils being connected in series and forming the energizing winding of the electromagnet. An armature 219 is mounted between a pair of spaced arms 221 pivotally supported on a pivot pin 223 mounted on the U-shaped frame 213. The lower end of an extension 225 rigidly secured to the free ends of the arms 221 is provided with an ear 227 in which is mounted an adjustable screw 229. The screw 229 is in alignment with an arm 231, similar to the previously described arms 185, secured to the trip bar 187 so that upon counterclockwise movement of the spaced arms 221 and the extension 225, the screw will rock the trip bar 187 clockwise to trip the breaker in the previously described manner.

The arm 221—225 is connected to the tie bar 67 of the breaker contact assemblage by means of a resilient linkage 245 (Figs. 1 and 4). The one end of the linkage is pivotally connected to the arms 221 by a pivot pin 233 mounted in the arms and the other end of the linkage is pivotally connected to the tie bar 67 by a pivot pin 235 projecting from the end of the tie bar.

The resilient linkage 245 includes a cylinder 261 (Figs. 1 and 4) provided with a transverse opening at one end through which the pivot pin 233 extends. A cylindrical sleeve 265 (Fig. 4) fitting in the end of the cylinder 261 which is connected to the spaced arms 221 is retained in place by the pin 233 which extends transversely through openings therein. A shoulder rod 267 having its upper end threaded into a connector 237 projects into the cylinder 261. The connector 237 has a transverse opening therein to receive the pin 235 which projects from the end of the tie bar 67 and thus serves to connect the upper end of the linkage 245 (Fig. 1) to the tie bar. A lock nut 239 is provided to lock the rod 267 and connector 237 in their adjusted positions. The other end of the rod 267 is provided with a screw 271 whose head is slidable in the sleeve 265. A spring 273 is compressed between a washer 275 seated against the inner end of the sleeve 265, and a washer 277 seated against the inner shoulder of the cylinder 261. The construction is such that the head of the screw 271 engages the washer 275, and the shoulder on the rod 267 engages the washer 277, so that the compression of the spring 273 in the cylinder will be increased when the rod 267 and the cylinder 261 are moved in either direction relative to each other.

As shown in Fig. 4, the spring 273 is given an initial compression, the expansion force of which presses the washers 275 and 277, respectively, against the sleeve 265 and the inner shoulder of the cylinder 261. The interlock device 208 is shown in Fig. 1 in the normal position, that is, with the circuit breaker contact assemblage in the closed contact position and normal control voltage applied to the coils 217 of the electromagnet 209 through a control circuit which will be described later. In this condition, the linkage 245 is in tension, i. e., the rod 267 is drawn partway out of the cylinder 261 giving the spring a greater compression than its initial compression. The tension of the linkage 245 in these circumstances, biases the arm 221—225 and the armature 219 in a counter-

clockwise direction or to unattracted position. Normal voltage in the control circuit however energizes the windings 217 of the electromagnet 209 sufficiently to hold the armature 219 and the trip arm 221—225 in the attracted positions against the bias of the resilient linkage 245 to prevent tripping of the breaker by the interlock trip arm 221—225.

Means is also provided to prevent tripping movement of the arm 221—225 due to deenergization of the magnet 209 upon the loss of control voltage when the main breaker contacts are in closed position. This means comprises a bell crank lever 279 (Fig. 1) which is pivotally supported on a pivot pin 281 mounted in the upper ends of a pair of brackets 283 (only one being shown) secured to the sides of the U-shaped frame 213. An open slot 234 in the end of the upwardly extending arm of the lever 279 embraces the pin 235 and transmits the movement of the tie bar 67 to the lever 279. The other end of the lever 279 is formed in the shape of a yoke 285 in which is mounted an adjustable screw 287 which is adapted to cooperate with a projection 289 of the interlock trip arm 221 when the main breaker contacts are in the closed contact position to prevent tripping movement of the arm 221—225 due to loss of control voltage of the interlock control circuit.

Referring now to Fig. 3, it can be seen that a circuit breaker of the type previously described and indicated schematically at A is closed connecting a main source circuit 3 to a load circuit 5, and that a second circuit breaker B is open disconnecting an auxiliary source circuit 4 from the load circuit 5. The breakers A and B are provided with auxiliary contacts 241a and 241b, respectively. The contacts 241a control the energization of the interlock magnet 209b for the breaker B, and the contacts 241b control the interlock magnet 209a for the breaker A. It can also be observed that the contacts 241a and 241b are open when their corresponding breaker is closed and closed when the corresponding breaker is open. Thus the magnet 209a is energized when breaker B is open and the magnet 209b is energized when breaker A is open. Conversely the magnet 209a is deenergized when breaker B is closed and magnet 209b is deenergized when breaker A is closed.

The control circuits for energizing the magnet 209a extends as follows: From a control supply conductor 247 through a conductor 249, auxiliary contacts 241b, a conductor 251, coils 217 of the magnet 209a, a conductor 253 to the supply conductor 255. Similarly the energizing circuit for the magnet 209b extends from the supply conductor 247, through a conductor 257, auxiliary contacts 241a, conductor 259, coils 217 of the magnet 209b and conductor 262 to the control supply conductor 255.

When the circuit breaker is in the open position, i. e., with the main contact assemblage including the tie bar 67 in the open position the arm 221—225 is retained by the resilient linkage 245 in the position shown in Fig. 1 with the armature 219 in contact with the core 211. The linkage transmits the clockwise or opening movement of the tie bar 67 to the spring 273. During the latter part of this movement the rod 267 telescopes into the cylinder 261 placing the linkage in compression, thereby holding the arm 221—225 in the position shown in Fig. 1 and permitting overtravel of the parts without subjecting them to undue strain. During the

movement of the contact assemblage to the open position, the bell crank lever 279 is rocked clockwise, due to the pin and slot connection 234—235, moving the screw 287 away from the projection 289.

Referring to Fig. 3, let it be assumed that the breaker B is in the open position, as just described, and that the breaker A is closed as illustrated in Fig. 1. It will be remembered that when the breaker was tripped open, the tripping toggle 107—109 was momentarily collapsed permitting the springs 85 to move the contact assemblage to the open position. Upon reaching the fully open position, the toggle 93—95 collapsed and the linkage including the lever 89, link 103, lever 105 and the tripping toggle 107—109 was restored to the normal position. The magnet 209b is deenergized due to the opening of contacts 241a of breaker A.

If, with the breaker B in this condition, the handle 141 is rotated in closing direction, the closing lever 145 will be rotated in clockwise direction to effect straightening of the operating toggle 93—95 as previously described. During the first part of this movement, the contact arm 30—31 will be rocked slightly in closing direction since the tripping toggle 107—109 is overcenter or in toggle at this time. The slight movement of the contact arm and the tie bar 67 again places the resilient linkage 245 in tension, thus transmitting the movement of the tie bar to the trip arm 221—225. This rocks the trip arm counterclockwise and by means of the screw 229 actuates the trip bar 187 which in turn thrusts the trip rod 135 upwardly and starts the tripping toggle 107—109 overcenter. The springs 85 then act to move the contact arm to the fully open position and to complete the collapse of the tripping toggle in the previously described manner.

It can be seen, therefore, that since neither the breakers A or B can be closed when the other is closed, the load circuit 5 may be connected to only one of the source circuits 3 or 4 at a time.

As previously described, the closed breaker may be automatically opened in response to an overload condition in the circuit controlled by the breaker. In this event either breaker may be manually closed since the control magnets 209a and 209b are both energized over their respective control contacts 241b and 241a. Energization of the magnet will attract the armature 219 with sufficient force to prevent tripping movement of the interlock trip arm 221—225. The tripping toggle 107—109 will, therefore, remain in the overcenter restraining position and the breaker may be closed in the usual manner. As the contact assemblage including the tie bar 67 (Fig. 1) is moved to closed position the linkage 245 is again placed in tension.

It was mentioned previously that it is desired to prevent the closed breaker from tripping open due to failure of energy in the control circuit 247—255. With the breaker in closed position, the tension of the spring 273 (Fig. 4) of the flexible linkage 245 is overcome by the attraction of the magnet 209 (Fig. 1) which prevents tripping operation of the interlock trip arm 221—225. If the source of control energy in the circuit 247—255 were to fail the linkage 245 ordinarily would immediately actuate the arm 221—225 to trip the breaker. Means comprising the bell crank 279 is provided to prevent such undesirable tripping action. From Fig. 1 it can be seen that when the breaker is in the closed position, the bell crank lever 279 is positively held in the

position shown due to the pin and slot connection 234—235. With the bell crank 279 held in its Fig. 1 position, the screw 287 positively holds the arm 221—225 in the attracted position against the tension of the flexible linkage 245 irrespective of the energized condition of the magnet 209.

From the foregoing description, it can be seen that there is provided a system of electrically interlocking two remotely located circuit breakers in a manner which permits only one of the circuit breakers to be closed at a time. There has also been provided a simple and effective mechanical means for preventing tripping out of the closed breaker due to loss of energy in the interlocking control circuit.

It is obvious that additional source circuits may be selectively connected to the load circuit and the circuit breakers for controlling the additional circuits may be interlocked with the other breakers by extending the energizing circuit for the control magnet for each breaker serially through auxiliary contacts on all of the other breakers.

Having described a preferred embodiment of the invention in accordance with the patent statutes, it is to be understood that various changes and modifications may be made therein without departing from some of the essential features of the invention. It is, therefore, desired that the appended claims be given as reasonably broad interpretation as the prior art permits.

I claim as my invention:

1. A circuit breaker comprising relatively movable contacts, operating mechanism for said contacts, a trip device operable to cause opening of the contacts, a second device operable to cause opening movement of said contacts, said second device when operated preventing closing of the breaker, spring means for biasing said second device to operated position, an electromagnet operative when energized to prevent operation of said second device, said electromagnet when de-energized permitting operation of said second device, and means effective when said contacts are in closed position to positively prevent operation of the second device irrespective of condition of the electromagnet.

2. A circuit breaker comprising relatively movable contacts, operating mechanism for said contacts, a trip device operable in response to predetermined conditions in the circuit controlled by the breaker to cause opening of the contacts, a trip mechanism including a resilient linkage operable during a closing movement of the movable contacts to cause opening of the contacts, an electromagnet having an armature operatively connected to the trip mechanism for restraining said trip mechanism when the electromagnet is energized, a control circuit including means operated by a second circuit breaker for energizing the electromagnet when said second breaker is in open position and for deenergizing the electromagnet when the second circuit breaker is closed, and means effective when the contacts of the first breaker are in closed position to positively restrain the trip mechanism irrespective of the energized condition of said electromagnet.

3. A circuit breaker comprising relatively movable contacts, a switch member movable to open and close said contacts, operating mechanism for moving said switch member to open and to closed circuit positions, a trip device including resilient means operable if unrestrained during closing movement of the switch member to cause opening movement of said switch member, an electromagnet responsive when energized to pre-

vent operation of said trip device, said electromagnet when deenergized permitting operation of the trip device to thereby prevent closing of the switch member, and means controlled by a second circuit breaker to control the energization of said electromagnet.

4. A circuit breaker comprising a switch member movable to an open and to a closed position, operating mechanism for moving said switch member to open and closed positions, a trip device including resilient means operatively connected to the switch member and operable during a closing movement of said switch member to initiate an opening movement of the switch member, an electromagnet operable when energized to restrain the trip device and permit a complete closing movement of the switch member, means operable by a second circuit breaker to control the energization of said electromagnet, and means operable when the switch member is in closed position to restrain the trip device independently of the electromagnet.

5. A circuit breaker comprising a switch member movable to an open and to a closed position, a trip device including resilient means operable during a closing movement of the switch member to initiate an opening movement of said switch member to thereby prevent closing of the switch member, an electromagnet effective when energized to prevent operation of said trip device, said electromagnet when deenergized permitting operation of the trip device to thereby prevent movement of the switch member to the fully closed position, means including a second circuit breaker for controlling the energization of said electromagnet, and a current responsive trip device operable in response to predetermined conditions in the circuit controlled by the first breaker to cause opening movement of the switch member irrespective of the energized condition of the electromagnet.

6. In combination, a pair of circuit breakers, each of said circuit breakers comprising relatively movable contacts, operating mechanism including a toggle operable to cause opening of said contacts which toggle in the operated position prevents closing of said contacts, a trip device including resilient means operable to cause operation of said toggle, an electromagnet having an armature operatively connected to the trip device for restraining said trip device against operation by the biasing force of said resilient means, said electromagnet when deenergized releasing the trip device for operation, and means operable by one of the breakers when said breaker is operated to closed position to deenergize the electromagnet for the other breaker and permit operation of the trip device.

7. The combination with two supply circuits and a load circuit, of a circuit breaker associated with each of said supply circuits for selectively connecting said supply circuits to said load circuit, each of said circuit breakers comprising relatively movable contacts, operating mechanism including a member movable to a position to cause opening movement of said contacts, said member when in said position preventing closing of said contacts, means biased to cause movement of said member to said position, an electromagnet having an armature operatively connected to said means for holding the means in operative position against the biasing action, said electromagnet when deenergized releasing the biased means for operation, means operable by one of said breakers when said breaker is op-

erated to closed position to effect deenergization of the electromagnet for the other breaker to thereby prevent operation of said other breaker to closed position, and means on each breaker operable when the breaker is in closed position to restrain the biased means independently of the electromagnet.

8. The combination with a circuit to be energized, a plurality of sources of energy therefor, and connecting means comprising a plurality of circuit breakers disposed between the circuit and each of the respective sources for selectively connecting said circuit to said sources, a device for each breaker operable to prevent closing of the associated breaker, an electromagnet associated with each device and operable when energized to prevent operation of said device, said magnet when deenergized permitting operation of its associated device, means on each of the breakers to control the energization of the electromagnet for the other of said breakers, and means on each breaker operable when said breaker is in closed position to positively prevent operation of the device independently of the electromagnet.

9. A circuit breaker comprising relatively movable contacts, operating mechanism for said contacts including a toggle operable to cause opening of said contacts, a current responsive trip device operable in response to predetermined circuit conditions for operating said toggle, means including a resilient linkage for operating the toggle to prevent closing of the contacts, an electromagnet energized under control of another circuit breaker and operable when energized to prevent operation of said means, and means operable when the first breaker is in closed position to positively prevent operation of said linkage independently of the electromagnet, said current responsive trip device being operable to cause opening of said contacts irrespective of the operative condition of the linkage.

10. A circuit breaker comprising relatively movable contacts, operating mechanism for said contacts, a member movable to a tripping position to cause opening movement of said contacts, said member preventing closing of said contacts when in said tripping position, resilient means operable to bias said member in one direction during initial closing movement of the breaker and when the breaker is in the closed position and in the opposite direction when the breaker is open, an electromagnet operable when energized to prevent movement of said member to tripping position, said electromagnet when deenergized permitting movement of said member to tripping position, and means effective when said contacts are in closed position to prevent movement of said member to tripping position irrespective of said electromagnet.

11. A circuit breaker comprising relatively movable contacts, operating mechanism for said contacts, a member movable to a position to effect opening movement of the breaker and to prevent closing of the breaker, means biasing said member to said position during the initial closing movement of the breaker and when the breaker is in closed position, an electromagnet effective when energized to prevent movement of the member to said position, and means effective when the contacts are in closed position for preventing movement of the member to said position irrespective of said electromagnet.

12. In combination, a plurality of circuit

breakers each having a member movable to a tripping position to cause opening of the breaker and to prevent closing of the breaker, resilient means biasing said member in one direction during initial closing movement of the breaker and when the breaker is in closed position and in the opposite direction when the breaker is open, an electromagnet effective when energized to prevent movement of said member to tripping position, said electromagnet when deenergized permitting movement of said member to tripping position, means for energizing said electromagnet, means effective when the contacts are in closed position to prevent movement of said member to tripping position, and means on each breaker operable when the breaker is closed to effect deenergization of the electromagnets of the other circuit breakers.

13. A circuit breaker comprising relatively movable contacts, operating mechanism for said contacts, a member movable to a tripping position to cause opening movement of said contacts, said member preventing closing of said contacts when in said tripping position, spring means for biasing said member to tripping position, an electromagnet operable when energized to prevent movement of said member to tripping position, said electromagnet when deenergized permitting movement of said member to tripping position, and means effective when said contacts are in closed position to prevent movement of said member to tripping position irrespective of said electromagnet.

14. In combination, a plurality of circuit breakers each having a member movable to a tripping position to cause opening of the breaker and to prevent closing of the breaker, spring means for biasing said member to tripping position, an electromagnet effective when energized to prevent movement of said member to tripping position, and means effective when said contacts are in closed position to prevent movement of said member to tripping position, said electromagnet when deenergized permitting movement of said member to tripping position, and means effective when said contacts are in closed position to prevent movement of said member to tripping position irrespective of said electromagnet.

15. A circuit breaker comprising relatively movable contacts, a switch member movable to an open and to a closed position, operating mechanism for moving said switch member to open and closed positions, a trip member movable to a tripping position to cause movement of said switch member to open position, said trip member preventing movement of the switch member to closed position when in said tripping position, resilient means operable by said switch member for biasing said trip member to tripping position during the initial closing movement of said switch member and when said switch member is in closed position, an electromagnet having an armature operatively connected to said trip member for holding the trip member against the biasing force of said resilient means, said electromagnet when deenergized releasing the trip member for movement to tripping position, and means operable by the switch member when said switch member is in the closed position to hold the trip member independently of the electromagnet.

ALBERT H. BAYLIS.
